COMBINED MIXER AND DISPENSER FOR ICE CREAM OR THE LIKE

Robert E. Wildman, New Augusta, Ind., assignor to General Equipment Manufacturing & Sales, Inc., Indianapolis, Ind., a corporation of Indiana

Filed Jan. 12, 1961, Ser. No. 63,513

Term of patent 14 years

(Cl. D2—3)

Fig. 1.

Fig. 2.

FIG. 1 is a side perspective view of a combined mixer and dispenser for ice cream or the like showing my new design.

FIG. 2 is a front perspective view thereof. The back of the combined mixer and dispenser is substantially plain.

I claim:

The ornamental design for a combined mixer and dispenser for ice cream or the like, as shown and described.
